UNITED STATES PATENT OFFICE

109,918

DESIGN FOR A COMBINATION BAGGAGE RACK AND LIGHTING FIXTURE OR SIMI- LAR ARTICLE

Sterling B. McDonald, Itasca, Ill., assignor to The
Adlake Company, a corporation of Illinois

Application October 27, 1937, Serial No. 72,442

Term of patent 14 years

To all whom it may concern:

Be it known that I, Sterling B. McDonald, a citizen of the United States of America and a resident of Itasca, county of Du Page, and State of Illinois, have invented a new, original, and ornamental Design for a Combination Baggage Rack and Lighting Fixture or Similar Article, of which the following is a specification, reference being had to the accompanying drawing, forming a part thereof, wherein

Fig. 1 is a perspective view of a combination

baggage rack and lighting fixture, showing my new design;

Fig. 2 is a bottom plan view of a fragmentary portion of the baggage rack; and

Fig. 3 is a section taken on the line 3—3 of Fig. 2.

I claim:

The ornamental design for a combination baggage rack and lighting fixture or similar article, substantially as shown.

STERLING B. McDONALD.
